The ornamental design for a self regulating fluid bearing high pressure rotary nozzle, as shown and described.

DESCRIPTION

FIG. 1 is a front perspective view of a self regulating fluid bearing high pressure rotary nozzle showing my new nozzle design.

FIG. 2 is a rear perspective view of my new nozzle design. FIG. 3 is one side elevational view of the nozzle shown in FIGS. 1 and 2, the opposite side elevational view being substantially identical thereto.

FIG. 4 is a side elevational view of the nozzle shown in FIGS. 1 and 2 rotated clockwise about its longitudinal axis 90 degrees from the view shown in FIG. 3.

FIG. 5 is a top plan view of the front end of the nozzle shown in FIGS. 1 and 2.

FIG. 6 is a bottom plan view of the rear end of the nozzle shown in FIGS. 1 and 2; and,

FIG. 7 is a longitudinal cross sectional view taken along line 7—7 of FIG. 1.
